UNITED STATES PATENT OFFICE.

SAMUEL L. POWELL, OF LEWISTOWN, ASSIGNOR OF ONE-HALF TO FREDERICK D. MORRISON, OF BALTIMORE, MARYLAND.

ELECTRICALLY-OPERATED RAILWAY-SWITCH.

SPECIFICATION forming part of Letters Patent No. 443,167, dated December 23, 1890.

Application filed February 21, 1890. Serial No. 341,314. (No model.)

To all whom it may concern:

Be it known that I, SAMUEL L. POWELL, a citizen of the United States, residing at Lewistown, in the county of Frederick and State 5 of Maryland, have invented a certain new and useful Improvement in Electrically-Operated Railway-Switches, of which the following is a full, clear, and exact description.

The object of this invention is to provide 10 for electrically operating railway-switches.

The invention comprises a switch-bar and switch-bar-actuating mechanism, which are set in motion and locked in given position by 15 electrically-actuated mechanism, as I will proceed now more particularly to set forth, and finally claim.

In the accompanying drawings illustrating 20 my invention, in the several figures of which like parts are similarly designated, Figure 1 is a plan view showing the switch mechanism and the electrically-operated actuating mechanism together with the circuits. Fig. 2 is a 25 perspective view of the electro-mechanical mechanism for shifting the switch-bar. Fig. 3 is a perspective view of a portion of the 30 switch-bar. Fig. 4 is a vertical longitudinal section, and Fig. 5 is a vertical cross-section, of one of the contacts on the track. Fig. 6 is a 35 sectional elevation of a modified form of contact. Fig. 7 is a plan view showing the 40 trolley carried by the train for operation in connection with one of the forms of track-contact. Fig. 8 is a perspective view of a switch-locking device. Fig. 9 is a sectional elevation of another form of switch-locking 45 device. Fig. 10 is a side elevation of the form of locking-bar used in Fig. 9. Fig. 11 shows in detail the slip-joint connection of the 50 switch-operating rods with their levers. Fig. 12 is a sectional elevation of the lever-hook.

The main track *a* and the siding *b* may be 55 as usual, with the switch-rails mounted upon the switch-bar *c*. This switch-bar is provided with loops *d*, in which is arranged an auxiliary switch-bar *c'*, to which the usual switch-stand and lever *e* may be applied for operating the switch by hand. The two bars *c* and *c'* are connected by means of a spring-bolt *f* on 60 the switch-bar *c* engaging a keeper *f'* on the switch-bar *c'*. When the bolt *f* is in en-

gagement with the keeper *f'*, the two switch-bars *c* and *c'* must move together; but when the bolt *f* is disengaged from the keeper *f'* then the switch-bar *c'* remains stationary while the switch-bar *c* may be moved. Connected to the bolt *f* is a lever *g*, one arm *g'* of which forms the armature of an electro-magnet *g*², and when this electro-magnet is energized it attracts its armature *g'*, withdraws the bolt *f* from the keeper *f'*, and permits the independent movement of the switch-bar *c*. The switch-bar *c* is engaged by one arm of a three-armed lever *h*, suitably secured—as, for example, to a tie or upon other suitable foundation. Rods *i* and *j* are loose-jointed 65 to the three-armed lever *h*, and these rods are extended for some distance beyond the switch and on either side thereof, so as to operate the switch from either side thereof by a moving train. The ends of the rods *i* and *j* are 70 provided with heads *i'* and *j'*, respectively, and these heads are adapted to be engaged by a lever-hook *k*. Opposite faces of this lever-hook are provided with notches *k'* *k'*, which are adapted to hook over one or the 75 other of the rods *i* and *j* back of their heads, and the said lever-hook is provided with a shank *k*², which is pivoted at *k*³ in an arm *l* of a rock-shaft *l'*, suitably mounted upon, for example, a cross-tie. A spring *l*² is arranged in an opening in the arm *l*, to act 80 upon the end of the shank *k*² in order normally to hold the lever-hook in an upright position, from which it may be shifted to engage one or the other of the rods *i*, *j*. To this 85 end the lever-hook has a lateral motion upon its pivot *k*³, and it is an armature for the electro-magnets *m* *m'*. A spring bolt or pin *k*⁴, secured to the tie or other fixture, is arranged centrally of the arm *l* in the plane of 90 the parting of the said arm and the lever-hook, so that when the said lever-hook is attracted by one or the other of the magnets the said spring-pin will project beneath one 95 of the notched portions to prevent the accidental return of the said lever-hook and its disengagement from the rod. As the lever-hook rocks with the rock-shaft it leaves the pin *k*⁴; but the strain put upon it by engagement with the rod holds the two against ac- 100

idental displacement. The rock-shaft l' has an arm l^3 , which is connected by means of a link l^4 with a lever n , that is pivoted alongside the rail so as to be engaged by the flange 5 of a wheel of a passing engine or car. This lever n is normally elevated by means of a spring n' or other device. Now it will be observed that if, for example, the magnet m' be energized it will attract the lever-hook k 10 to it and the said lever-hook will engage the rod i . If the lever n be then depressed, the rock-shaft l' will be rotated within its bearings and the lever-hook will be thrown outward in the direction of the arrow, Fig. 2, and 15 carry with it the rod i , and the said rod, acting upon the lever h , will reverse the movement of the switch through the switch-bar c from the position shown in Fig. 1 to the position opposite. The switch parts will be 20 stored to the position shown in Fig. 1 by the attraction of the lever-hook by the electro-magnet m and the engagement of the said lever-hook with the rod j , as is obvious.

The track at each side of the switch is provided with contact-pieces o , and similar provision is made in the siding, and these contact-pieces are connected by suitable electric conductors with the electro-magnets m m' and g^2 in independently-operable circuits, it 25 being understood of course that the electro-magnet g^2 forms a part of the circuits for the contact-pieces on each side of the switch in the main track and for those in the siding.

Various forms of contact-pieces may be employed. Referring to Figs. 4 and 5, the contact-pieces may consist of an electrically-insulated casing o' , in which are arranged the two conducting-strips o^2 , which are normally projected by means of springs o^3 , and I prefer to arrange the strips o^2 upon a common insulated base o^4 , which is supported upon the springs o^3 . In connection with this form of contact-pieces I may employ upon the engine or a car a rolling contact-piece p , Fig. 7, 30 which is composed of two pieces of conducting material insulated from one another and insulated from their common shaft p' and adapted to be moved laterally upon said shaft to engage one or the other of the pairs of contact-pieces, and this rolling contact may be 35 connected with the source of electrical supply—such as a battery A, Fig. 1—by means of wires and brushes p^2 . Instead of this form of electrical connection, I may provide the car-wheel q with electric conductors q' , properly insulated from the wheel, and on that side of the rail next to the tread I may provide the spring-pressed horizontal contact r , and on the other side the spring-pressed vertical contact r' ; but I wish it to be understood that I do not limit my invention to any 40 of the mere details of the electric circuits.

In order to prevent the undesirable shifting of the switch while the train is in motion and 45 after it has been set, I may arrange in the track a switch-locking device—such, for example, as those shown in Figs. 8, 9, and 10.

In Fig. 8 this switch-locking device consists of a bar s , supported upon cranks s^1 and connected by a crank-rod s^2 with the switch-bar 70 in such manner that when the wheel of the car is upon the bar s the switch-bar will be held against movement. Instead of mounting the bar s upon cranks, its lower edge may be notched, as shown in Fig. 10, and mounted 75 upon rollers s^3 , secured to the ties in brackets s^4 . Or, instead of either of these forms of switch-locking device, I may employ the rocking plate t , (see Fig. 1,) which is connected immediately by a crank-rod to the switch-bar, 80 to serve the same purpose. Any other form of switch-locking mechanism may be employed, my invention in this particular consisting, broadly, in the combination, with an electrically-operated switch-bar, of a switch-bar, lock- 85 ing mechanism held by the passing train.

With respect to the conducting-wheel on the train it is to be observed that it is composed of two conductors, and these are connected with opposite poles of the source of 90 electricity. By this means I insure a complete circuit.

One of the track-contacts of each of the various pairs of contacts o is so connected by the electric conductors and magnets with the 95 switch-bar that the switch may be set at any time to open the main track. Hence the electrical apparatus on the train is capable of being set so that no matter what switches may be open on the track the train is traveling on, 100 the said train mechanism will automatically set all switches for the main track. In the case of the trolley, Fig. 7, the said trolley may be shifted to act upon that contact-piece which must be put in circuit, it being the 105 right-hand one (shown in Fig. 1) or that one midway between the track-rails, and so in the case of the device shown in Fig. 6 the flanged sides of the pair of wheels of the train will be kept in circuit to operate the switch to 110 open the main track.

As shown in Fig. 1, the switch is set for the siding, and the train mechanism is in contact with the track-contacts which are in the center of the track, and the train is approaching 115 the switch. Now, if the train mechanism be energized the first action is to energize the switch-bar magnet and unlock these bars, so as to permit the upper bar to be shifted by the electro-mechanical devices. The circuit 120 is made through wires 2 3. The magnet m' is energized at the same time through wires 4 5, and attracts the lever-hook into engagement with rod i , so that as lever n is acted upon by the car-wheel the rod i will be pulled 125 toward the train and the switch set for the main track. All the other wires during this operation are incomplete circuits, and hence are inoperative. Should it be desired to reset the switch for the siding so as to close the 130 main track against a train in the rear, the proper track-contact to the right of the switch in the drawings will be engaged and the magnet m' put in circuit t by wires 6 and 7.

Should the main track be left open and it be desired to open the siding, then magnet *m* 5 may be energized through wires 5 8. The wires 9 10 connect the track-contacts at the 5 right of the switch in the drawings with the magnet on the switch-bar.

What I claim is—

1. In a railway-switch, a switch-bar, a lever connected thereto, rods connected to said lever to move it in opposite directions, a lever-hook pivoted in its support and adapted to be moved toward and engage one or the other of the said rods, a rock-shaft in which the said lever-hook is supported, and means 15 whereby the said rock-shaft may be actuated by a passing train, combined with electro-magnets arranged at opposite sides of the lever-hook to attract the said lever-hook as an armature into engagement with one or the other of the said rods, and an electric circuit completed and rendered operative by connection with a passing train, and including the said electro-magnets, substantially as described.
2. In a railway-switch, a switch-bar provided with a bolt, an electro-magnet, and an armature interposed between the electro-magnet and the said bolt for retracting the said bolt, and a hand-operated switch-bar adapted 30 to be engaged by the said bolt to lock the two switch-bars together, a lever connected to that switch-bar which carries the electro-magnet, rods connected to said lever to move it in opposite directions, a lever-hook pivoted in its support and adapted to be moved toward and engage one or the other of the said rods, a 35 rock-shaft in which the said lever-hook is supported, and means whereby the said rock-shaft may be actuated by a passing train, combined with electro-magnets arranged at opposite sides of the lever-hook to attract the said lever-hook as an armature into engagement with one or the other of the said rods, and an electric circuit completed and rendered operative 45 by connection with a passing train, and including the said electro-magnets and also the electro-magnet on the switch-bar, substantially as described.
3. In a railway-switch, a switch-bar, a lever connected thereto, rods connected to said lever to move it in opposite directions, a lever-hook pivoted in its support and adapted to be moved toward and engage one or the other 50

of the said rods, a rock-shaft in which the said lever-hook is supported, and means 55 whereby the said rock-shaft may be actuated by a passing train, combined with electro-magnets arranged at opposite sides of the lever-hook to attract the said lever-hook as an armature into engagement with one or the other of the said rods, and an electric circuit completed and rendered operative by connection with a passing train, and including the said electro-magnets, and a switch-locking mechanism to hold the switch in position 60 while a train is passing, substantially as described.

4. In a railway-switch, a rock-shaft connected to and operated by a lever, which in turn is actuated by a passing train, an armature pivoted in said rock-shaft and adapted to move with the said rock-shaft and also to have a lateral motion therein, rods arranged in position to be engaged by the said armature by lateral movement thereof and to be 75 moved longitudinally by the rocking motion of the shaft, and lever-connections of said rods with a switch-bar, combined with electro-magnets for attracting the armature into engagement with one or the other of the rods, 80 and an electric circuit rendered operative from a passing train, substantially as and for the purpose described.

5. In an electrically-operated railway-switch mechanism, an electro-mechanical 85 switch-operating mechanism for shifting the switch to open the main track, including contact-pieces in the track, each comprising two members for simultaneous connection with opposite poles of a source of electricity, combined with an electric mechanism on the train, comprising a conductor connected with the opposite poles of a source of electricity and adapted to contact with the electrically similar track-contacts, and so complete a leading 90 and a return circuit to actuate such switch mechanism normally and automatically to open the main track, substantially as described.

In testimony whereof I have hereunto set 100 my hand this 19th day of February, A. D. 1890.

SAMUEL L. POWELL.
